UNITED STATES PATENT OFFICE.

JOHN WOLDEMAR RUBEN, OF PORTLAND, OREGON.

SOARING AEROPLANE.

1,225,059.

Specification of Letters Patent.

Patented May 8, 1917.

Application filed July 19, 1915. Serial No. 40,787.

To all whom it may concern:

Be it known that I, JOHN WOLDEMAR RUBEN, a subject of Russia, residing at Portland, in the county of Multnomah and 5 State of Oregon, have invented a new and useful Soaring Aeroplane, of which the following is the specification.

My invention relates to improvements in heavier than air flying machines in which, 10 by the combination of air pressure and gravity I obtain forward motion; and the objects of my invention are: first, to provide means for soaring flight as practised by the birds; second, to provide a flying machine 15 that will maintain its equilibrium in all conditions having very high lateral and longitudinal stability and always will keep in proper angle of incidence with respect to the head pressure; third, to provide a flying machine with high lifting capacity; 20 fourth, to provide a flying machine with very little head friction and fifth, to provide means for flying against the strong winds as well as with the wind, thus over- 25 coming conditions known as air pockets which are nothing but strong rear gusts.

To attain these results I use mechanism illustrated in the accompanying drawing in which Figure 1 is a view of the front elevation 30 of the machine, Fig. 2 a plan view, Fig. 3 a side view and Fig. 4 a view of the wing controlling mechanism. Referring to the drawings in detail, (7) indicates the body or frame of the device which is tor- 35pedo shaped and covered with any suitable material adapted to inclose pilot's seat (1), steering wheel (2) and motor (3) which is to rotate a propeller (5) placed on front of the machine. Two main planes (6) are pro- 40jecting upward from the body in dihedral angle of 150° on the leading margin and 127° on the rear margin of the planes. Said planes being pterygoidal, are rather wide, close to the body, sloped down very narrow 45 to the outer tips in high aspect ratio. Each of the main planes consists of two diversely inclined surfaces, proportions of which surfaces can be increased or decreased accord- 50ing to increased or decreased angle of the diversely inclined surfaces relatively to the angle of the main planes with respect to each other as said planes are pivotally se- 55cured at (4) and adapted to swing in a horizontal line along the longitudinal axis of the body. The main planes are arch shaped, curved slightly close to the body but

more pronouncedly at the outer extremities; each plane comprises two lateral wing bars (17) and (14) respectively, connected with cross bars or ribs and covered on both sides 60 with any suitable fabric. Outer portions (16) of the rear bars (14), representing about one half of the total length are of some flexible construction, preferably of flat steel spring that would bend upwardly in 65 the middle by pulling on wires (32), fastened on the wing tips and actuated by the steering mechanism. The centers of the flexible parts (16) are adapted not to bend downwardly and when the actuating wires 70 are loose they will follow the line of curvature of the bars (17); by pulling on the wires (32) declination of the parts (16) will be increased and decreased by letting the wires loose thus increasing the angle between two distinctly inclined surfaces necessary for any particular head pressure. Cross ribs of the flexible portions are loosely secured to the wing bars in order to yield when the angle between two diversely inclined surfaces is altered.

To actuate the wings I provide the mechanism illustrated in Fig. 4. On the rod (29) adapted to receive steering wheel (2), drum 30 is securely placed, around which wires 31 are wound in the same direction, each end of the said wires being secured to the shifting rods (8) at (34) and (35) respectively; by rotating the steering wheel with the drum on its shaft, the main planes are shifted forward or backward as the rods (8) are loosely connected to the cross ribs (10) at point (9). I employ this device for the shifting of the main planes along the longitudinal axis of the body with respect to each other, in order to keep in longitudinal stability and to obtain the best soaring angle in any particular head pressure, also, for the vertical steering with conjunction of flexible surfaces on the outer tips which are actuated by the wires (32) wound on drum (30) in the manner that they are tightened when main planes are swept backward and loosened when the main planes are moved forward thus allowing the elastic part of the outer portions to come to normal.

For the purpose of the shifting of the main planes in different angles, with respect to the longitudinal axis of the body, necessary for the horizontal steering, I provide bars (12), shaped like the arc of a circle, loosely connected with the main planes passing

through the slots (13), slideable with the steering rod (29) but adapted to be interlocked or released with said steering rod at the operator's will, for which purpose 5 any interlocking means can be used.

Bars (12) are connected to steering rod (29) above the point where said rod is connected by a joint to one of the bars in bottom of the body in a manner to turn around 10 said rod (29) with steering wheel (2) and also, to swing to right or left. Thus, with aid of the bars (12), the angle between the longitudinal axis of the body and each wing respectively is increased or decreased without 15 variation of angular relations between distinctly inclined surfaces.

In addition with two main planes I employ a horizontal rudder (18) actuated between trusses (20) by the wires (23) which 20 passing through the pulleys on the ends of bar (21), are connected with the second steering wheel (33) placed in the hood on the left side of the pilot's seat. Trusses (20) and (22) are secured to the rear extremity 25 of the chassis. The shape of this rudder is that of an elongated circle, pointed down in the direction of advance with sufficient surface area and leverage to keep the whole machine in horizontal line.

30 For the starting and alighting purposes I prefer to use two front wheels (24) secured to the body by rods (25) and (26) respectively. A third wheel (27) is placed under the rear end of the body, secured to the tail 35 by rods (28).

The operation of the device is as follows:—

When the steering wheel (2) with drum (30) on its shaft is rotated in the way so 40 the main planes are swept back, pull will be exerted on the flexible parts of the outer tips of the wings by wires (32) as said wires are wound around the same drum (30). This will cause the outer portions of the 45 wings to take a negative angle with respect to upwardly inclined parts, increasing this angle when the planes are moved backward and decreasing when the planes are shifted forward. By shifting the main planes backward until the downwardly inclined parts of the outer tips of the planes come behind the upwardly inclined center—this being in an angle of 6° with respect to the horizontal, I obtain very high lifting capacity. 50 If the center of gravity were coincident with the center of pressure, the whole machine would soar up at a very steep angle, but by the shifting of wings backward, the center of gravity is placed way in front of 55 the center of pressure. Thus by the aid of gravity, the steep upward climb is converted into straight horizontal soaring, provided, sufficient head pressure is supplied by the wind or by propelling the whole through 60 the air. To keep in the best angle of soara-

bility and to maintain longitudinal stability the main planes are shifted backward when the head pressure increases and forward when the head pressure decreases.

In order to execute soaring it is necessary 70 to provide a horizontal rudder for the purpose of keeping whole machine in a horizontal line and in proper angle of incidence. This rudder might be stationary as far as soaring and steering in normal conditions are concerned but to meet abnormal 75 conditions of flying, I have provided means for vertical actuating of this rudder around a horizontal axis.

Vertical steering is accomplished by the 80 forward and backward movement of the main planes; when the center of gravity is brought in front of the center of pressure by moving main planes backward, the machine will tend to glide down and the opposite will take place when by the shifting of wings forward, the center of gravity is placed behind the center of pressure. Horizontal steering, also, is accomplished by the 85 shifting of the main planes only, for this 90 purpose the angular relation of the main planes with respect to each other, as well as the angle between two diversely inclined surfaces remains unchanged while the angle 95 of each plane, with respect to the longitudinal axis of the body, is changed by the 100 swinging of the steering wheel with shaft (29), to the right or left as the shaft (29) is adapted to engage bars (12) which are connected to the main planes in any manner suitable for horizontal shifting of the main planes. By the swinging of the steering 105 wheel with shaft (29) to the right, the right wing will be advanced forwardly while the left plane will be moved backwardly and this will cause the whole machine to turn to the right as the more advanced right wing will be retarded, at the same time presenting more of the downwardly inclined area to the head pressure, said wing will tend to 110 sink down and consequently raise the other wing thus performing a horizontal turn in perfect equilibrium.

Reverse will take place when steering wing is swung to the left.

To add to the stability the center of gravity is placed below the sustaining surfaces, only the outer tips of the main planes, which are more curved, are projecting below the center of weight. The above described combination of the surfaces enables me to operate my device with one half of the power used on present flying machines or will double the speed if full power is employed. I do not wish to be understood 120 as limiting myself strictly to the precise details of construction hereinbefore described and shown in accompanying drawings as it is obvious that these details may be modified 125 without departing from the principles of 130

my invention. For instance, while I prefer the construction illustrated in which controlling of the main planes is accomplished by the sliding rods (8) with combination of the wires, the same results may be obtained by different gearing or by the spring made to yield to certain air pressures and shifting the wings accordingly. In the same way the flexible parts (16) of the main planes could be constructed in several distinct ways.

Having thus fully described my invention, what I claim as new and desire to secure by Letters Patent is:—

1. In a soaring aeroplane of the character described comprising a torpedo shaped body, two pterygoidal arch shaped planes projecting upwardly from the body in a dihedral angle, fast with respect to the vertical axis, movable in a wide angle along the longitudinal axis of the body; said planes being helicoidal each consisting of two diversely inclined surfaces each half of the length of the wing inclined in a negative angle with respect to the other half, means for increasing or decreasing the angular relations between two diversely inclined surfaces, means for moving the main planes along the longitudinal axis of the body in unison with the variation of the angle of inclination of the negatively inclined surfaces on the outer wing tips, substantially as and for the purpose specified.

2. In a soaring aeroplane of the character described comprising a torpedo-like body, two pterygoidal, arch shaped planes projecting upwardly from the body in a dihedral angle, fast with respect to the vertical axis, movable in a wide angle along the longitudinal axis of the body; said planes being helicoidal each consisting of two diversely inclined surfaces, each half of the length of the plane inclined in a negative angle with respect to the other half, means

for increasing or decreasing the angular relations between two diversely inclined surfaces, means for moving the main planes along the longitudinal axis of the body in unison with the variation of the angle of inclination of the negatively inclined surfaces on the outer wing tips, and means for shifting each of the main planes in an angle with respect to the longitudinal axis of the body independently of the downwardly inclined surfaces for the purpose of horizontal steering.

3. In a soaring aeroplane of the character described comprising a torpedo-like body, two pterygoidal, arch shaped planes projecting upwardly from the body in a dihedral angle, fast with respect to the vertical axis, movable in a wide angle along the longitudinal axis of the body; said planes being helicoidal with high aspect ratio, each consisting of two diversely inclined surfaces, each half of the length of the wing inclined in a negative angle with respect to the other half, means for increasing or decreasing the angular relations between two diversely inclined surfaces, means for the moving of main planes along the longitudinal axis of the body in unison with the variations of the angle of inclination of the negatively inclined surfaces on the outer wing tips, means for the shifting each of the main planes in an angle with respect to the longitudinal axis of the body independently of the downwardly inclined surfaces; above described surfaces in a combination with a horizontal rudder adapted to keep the main supporting planes in a proper angle of attack, and means for manipulating said rudder, substantially as and for the purpose specified.

JOHN VOLDEMAR RUBEN.
